SHANK BUTTON HOLDER

Jacob Brussell, New York, N. Y.

Application March 18, 1941 Serial No. 282,920

5. Claims

This invention relates to button sewing machines, more particularly to a device adapted to be attached thereto whereby to hold buttons, particularly those of the shank type, in proper positioning for attachment to a garment.

In the prior art, numerous devices of this character have been proposed and a number of them are in use. While some such devices may be satisfactory in operation, they are quite complicated in construction and are relatively expensive. Also, because of the complicated character of the devices, they are not sufficiently sturdy in many cases for the necessary work, particularly in modern high speed sewing machines. Furthermore, the repair of such devices is quite difficult.

The present invention has among its objects to overcome the difficulties and disadvantages heretofore encountered in devices of the character set forth above, and to provide a device which is simple and compact, sturdy and strong, and which will hold a button firmly in place during the sewing operation.

In practicing the present invention, I provide an attachment for a sewing machine in which there is as an essential feature a substantially horizontal extension on a base which is attached to the sewing machine. The extension forms the stationary jaw of a button holder, the other jaw being pivoted to the base of the device and held in substantial contact with the first named jaw by spring pressure. A space is provided between the jaws sufficient to allow the passage of a needle, the jaws being adapted to hold the shank of a button and the needle adapted to pass through the eye thereof and through the fabric to which the button is to be sewed.

In the accompanying drawing, constituting a part hereof, and in which like reference characters indicate like parts,

Fig. 1 is a top plan view of a device made in accordance with the present invention, showing in broken lines a button held by said device;

Fig. 2 is a longitudinal, cross-sectional view of the device taken along the line 2-2 of Fig. 1, some parts being shown in elevation for clearness;

Fig. 3 is a front, elevational view of the device with no button in place and indicating the position of the jaws when not in operation; and

Fig. 4 is a cross-sectional view taken along the line 4-4 of Fig. 1.

The base 1 is suitably formed so as to be attached to a desired part of the sewing machine for holding the device in the proper position relative to the sewing machine needle and associated

I. 112-114

30-1171-11
operating parts. From the lower end of base 1 a substantially horizontal extension 2 projects in the direction of the needle and terminates in a jaw 3. A similar jaw 4 extending from a base portion 5, which is pivoted to extension 2 at 6, is also in horizontal position in practically parallel relation to jaw 3. As shown in Fig. 1, jaws 3 and 4 are spaced a relative short distance apart to allow the passage of a needle between the same when in use.

The adjacent sides of said jaws 3 and 4 are provided with cut-out portions 7 and 8, respectively, the shape thereof approximating the shape of the eye of a shank button. Jaws 3 and 4 are also provided with recesses 9 and 10 of such character as to allow the entrance into the same of the shank of such a button which is guided thereto by means of grooves 22 at the outer ends of the jaws. A flat spring 11 has one end pressed against the outside of jaw 4, biasing it towards stationary jaw 3, and the other end 12 is secured to extension 2 by screws 13.

A button 14, having a shank 15, is inserted into recesses 9 and 10 and is held by the pressure of spring 11 in proper position. In order to prevent lateral motion of the button during the sewing operation, a pair of contact members 16 extend upwardly from bases 17, which are secured by slot and screw arrangements 18 and 19, respectively, on the upper surface of jaws 3 and 4. The shape and size of members 16 is such as to contact with the adjacent surface of button 14 and thus hold it firmly in position.

In operation, the button is held as shown in Fig. 1, and the needle is caused to sew the button onto the fabric by a vibratory motion in which during one stroke the needle passes through the eye 15 and in the next stroke passes to the left thereof. This cycle is repeated until the desired number of stitches is obtained. In the alternative, the needle may merely reciprocate without vibrating and the button holder be caused to vibrate, through suitable mechanism, in operative relation with base 1 of the device. When in operation, the position of extensions 16, as shown in Fig. 4, is such that a narrow space 20 is provided between the same. Therefore, after the button has been sewed to the fabric, it allows a ready removal of the finished product from the device. The assembly is such that ordinarily when not in operation, the members 16 are substantially in contact, as shown at 21 in Fig. 2.

The present invention provides an extremely simple construction which is easy to operate and which is positive in its action. The operator has

no adjustments to make except when a different type of button is being used, members 16 may require a slight adjustment by operation of the screw and slot arrangements. Otherwise, the device without any adjustment is capable of operating with various sizes and shapes of shank buttons. This device is highly desirable for use with high speed machines where the time element for introducing buttons and removing the sewed product consumed many times the time necessary for sewing operation. Therefore, a considerable advantage in the present invention lies in the much greater speed of introduction of buttons into the sewing operations. Furthermore, the device is strong and sturdy and has been found by ample tests to withstand the severe services necessary in machines operating at as high as 3600 revolutions per minute.

Although I have described my invention setting forth a single embodiment thereof, it will be apparent to those skilled in the art that various changes in the details of construction may be made in the invention within the scope thereof. Various changes in the means for attaching the device to a sewing machine may be provided and the form and arrangement of parts may be varied at will. Therefore, the invention is to be broadly construed and not to be limited except by the character of the claims appended hereto.

What I claim is:

1. A shank button holder for sewing machines comprising a base member adapted to be secured to a sewing machine, a substantially horizontal rigid extension thereon terminating in a rigid fixed jaw, a second rigid jaw cooperating therewith and pivoted to said extension, means for biasing said second jaw toward said first jaw, the adjacent sides of said jaws normally contacting under the action of said biasing means and having cooperating means for receiving the shank of a button for passage of a needle therethrough between the jaws when separated by said shank.

2. A shank button holder for sewing machines comprising a base member adapted to be secured to a sewing machine, a substantially horizontal rigid extension thereon terminating in a rigid fixed jaw, a second rigid jaw cooperating therewith and pivoted to said extension, means for biasing said second jaw toward said first jaw, the adjacent sides of said jaws normally contacting under the action of said biasing means and having cooperating means for receiving the shank of a button for passage of a needle therethrough between the jaws when separated by said shank, and means on each of said jaws adapted to contact with that side of a shank

button adjacent to its shank to prevent movement thereof during sewing.

3. A shank button holder for sewing machines comprising a base member adapted to be secured to a sewing machine, a substantially horizontal rigid extension thereon terminating in a rigid fixed jaw, a second rigid jaw cooperating therewith and pivoted to said extension, means for biasing said second jaw toward said first jaw, the adjacent sides of said jaws normally contacting under the action of said biasing means and having cooperating means for receiving the shank of a button for passage of a needle therethrough between the jaws when separated by said shank, and means on each of said jaws adapted to contact with that side of a shank button adjacent to its shank to prevent movement thereof during sewing and including fingers extending upwardly at the outer ends of said jaws.

4. A shank button holder for sewing machines comprising a base member adapted to be secured to a sewing machine, a substantially horizontal rigid extension thereon terminating in a rigid fixed jaw, a second rigid jaw cooperating therewith and pivoted to said extension, means for biasing said second jaw toward said first jaw, the adjacent sides of said jaws normally contacting under the action of said biasing means and having cooperating means for receiving the shank of a button for passage of a needle therethrough between the jaws when separated by said shank, and means on each of said jaws adapted to contact with that side of a shank button adjacent to its shank to prevent movement thereof during sewing and including fingers extending upwardly at the outer ends of said jaws, and means for adjusting the position of said fingers on said jaws.

5. A shank button holder for sewing machines comprising a base member adapted to be secured to a sewing machine, a substantially horizontal rigid extension thereon terminating in a rigid fixed jaw, a second rigid jaw cooperating therewith and pivoted to said extension, means for biasing said second jaw toward said first jaw, the adjacent sides of said jaws normally contacting under the action of said biasing means and having cooperating means for receiving the shank of a button for passage of a needle therethrough between the jaws when separated by said shank, and grooves at the outer ends of said jaws adapted to guide the shank of a button into the space between said jaws.

JACOB BRUSSELL.
